WHEEL AND METHOD OF MAKING SAME

Alfred T. Kvarnstrom, Detroit, Mich., assignor of
one-half to Bert L. Quarnstrom, Detroit, Mich.

Application July 17, 1933, Serial No. 680,881

8 Claims. (Cl. 208—181)

This invention relates to a wheel or roller, and to a method of making the same. The invention is concerned particularly with a small wheel useful on roller skates.

5 Among the objects of the invention is the provision of a better wheel over those which have heretofore been provided in that it has a greater life, or in other words, lasts longer and a wheel which gives silent operation. Also the invention 10 aims to provide a wheel of simplified structure and a method of making the same which, at least in part, makes it feasible to provide a strong wheel involving the simple structure. These objects as well as others will become more apparent 15 as the detailed description is considered in connection with the accompanying drawing.

Fig. 1 is a sectional view taken through a punch and die illustrating one of the first operations in the making of the wheel.

20 Fig. 2 is a view similar to Fig. 1 illustrating an operation on another part of the wheel.

Fig. 3 is a sectional view of the wheel having the parts assembled and prior to the final operation.

25 Fig. 4 shows the completed wheel in cross section.

Fig. 5 is a cross sectional view of a modified form of the wheel.

Fig. 6 is a side view thereof.
30 The main part of the wheel, which is the ground engaging part is formed advantageously from a blank of suitable metal, such as steel. This blank may be subjected to a forming operation by a punch 1 and a die 2. This part of the wheel 35 is shown at 3 and, as illustrated in Fig. 1, the center portion is punched out to provide an aperture 4. The aperture may be punched in the blank at any suitable time in the process of making the wheel either before the punch and die 40 operation illustrated in Fig. 1, during the punch and die operation, or following such operation.

The blank immediately surrounding the opening is fashioned to form a conical shaped part 5 and an intermediate part 6 which may lie perpendicularly to the axis. Between the part 6 and the rim, the metal may be formed generally into a bead or the like, as illustrated at 7, the rim part being illustrated at 8. In this operation the flange or rim 8, being erected from a substantially 50 flat sheet, is caused to be positioned in an area having a smaller diameter than that of the original blank. Accordingly, there is a certain amount of excess metal to be taken care of, and this is used to advantage in the present invention. This 55 excess metal flows and is made to result in a

thickening of the flange or rim 8 as illustrated in Fig. 1. Fig. 1 shows this in an exaggerated manner for the purpose of clearness. As a specific example, it may be mentioned that the original blank stock for the part 3 may be .093 inch in thickness, and after it is formed as shown in Fig. 1, the dimension across the free edge of the flange may be substantially .111 inch. Therefore, it will be seen that the thickening action results in the differential of .018 inch. The die 2 is provided with the recess, the walls of which are inclined outwardly as illustrated at 9, while the punch is preferably shaped so that its side walls parallel the axis. Accordingly, the outside surface of the rim or flange 8 is slightly conical in 15 shape as at 10 (Fig. 3) whereas the inside walls 11 are preferably parallel to the axis.

A second blank may be formed as shown in Fig. 2 with a punch 12 and die 13. This blank, generally referenced 15, is preferably of metal 20 thinner than the part 3, as for example, .037 inch. This part 15 is provided with a central aperture 16, a conical shaped portion surrounding the aperture as at 17, an intermediate portion 18, and a flange 19. It may be that in the 25 forming of the part 15 that the flange 19 will be thickened somewhat unless the dies are designed to prevent this thickening, but this is a matter of no particular importance as the flange 19 may be allowed to thicken or may be prevented from 30 thickening.

At this point it is to be pointed out that the dimensions given above for the metal thickness, etc., are exemplary only of stock which may be used to make a wheel, it being understood that 35 other dimensions may be employed.

After the two parts 3 and 15 are formed, the wheel may be assembled, and there is only one other major part, and this comprises a hub 20 having a circumferential groove 21 for ball bearings 22.

The assembly is as follows: Suitable jigs or the like may be provided for holding the hub and part 3 in proper association and a suitable number of balls 22 may be disposed in their proper 45 position. These balls may be free or they may be held by a cage. The part 15 is now telescoped into the cup-shaped member 3 as shown in Fig. 3. Preferably the member 15 fits tightly within the member 3 and the fit may be what is termed 50 as a press fit. For this purpose the outside diameter of the flange 19 may be slightly greater than the inside diameter of the rim 8. This differential for example may be .018 inch and it is to be understood that this is an example 55

only and that the invention is not limited thereto.

The two members 15 and 3 are brought together until their intermediate portions 6 and 18 come flush against each other, at which time the parts are in proper cooperating position. The conical portions 5 and 17 form races for the balls and the angularity of these parts and other dimensions are such that when the parts 15 and 3 are brought together with their intermediate portions flush against each other, that a nice bearing fit is provided. In other words, the balls fit nicely within the groove 21 and cone portions 5 and 17.

Now it will be observed that the outer face 10 of the wheel does not parallel the axis and to complete the wheel, the rim 8 is fashioned inwardly by pressure through the use of any suitable means bringing the parts to the position shown in Fig. 4. This results in bringing the outer face 10 substantially parallel with the axis and the inner face of the rim 8 takes a position at an angle to the axis and at the same time the flange 19 is caused to become angularly disposed.

Accordingly, the member 15 is held tightly in position flush against the intermediate part 6 and cannot be dislocated. In short, the open side of the cup-shaped member 3 has a diameter less than the maximum diameter of the member 15 and the member 3 is of re-entrant formation.

After the parts 3 and 15 are fashioned as illustrated in Figs. 1 and 2 and before they are assembled together they are then preferably subjected to a hardening treatment. Advantageously the hardening treatment may be such as to result in what is known as case hardening leaving the underlying portions of the metal relatively soft. This provides hardened surfaces for contacting with the ball bearings, and it may be pointed out that the hub 20 and the bearings are suitably hardened before assembly. This also provides a hardened contact surface at the rim of the wheel. By leaving the underlying portions of the metal soft or unhardened, particularly in the rim 8, the danger of cracking or breaking the metal in the rim when it is fashioned from the position shown in Fig. 3 to the position shown in Fig. 4 is minimized.

It will be observed that the wheel consists of a minimum number of parts comprising essentially three main parts, namely, the hub, the portion 3, and the portion 15. Of course, the ball bearings are in addition to these parts. It will also be noted that a minimum number of operations are required and that no welding or other means for securing the parts 15 and 3 together are necessary.

The modified form shown in Figs. 5 and 6 has, in addition to the above described wheel, raised portions 25 formed in the member 15. These extend radially as shown in Fig. 6, and have the appearance of spokes. This adds strength to the wheel and also adds to its appearance. These raised portions form channels between the abutting parts 6 and 15, as shown at 26, and one or more apertures 27 may be provided, advantageously in the member 3, so that dust and other extraneous matter which may gain access to the bearing may be removed by centrifugal action, the material passing out through the channels 26 and apertures 27.

While this wheel is of simple construction yet actual tests have shown it to be a highly efficient wheel having a life greater than other wheels now

used on roller skates. Other known wheels now in use, after considerable wear, stretch or widen out at the rim or ground engaging portion. The metal becomes worn and thin and the constant use may be likened to striking the metal with a hammer thus tending to thin the metal and spread it out axially. This spreading does not occur with the wheel of this invention. Another important feature of the wheel, which is an object of the invention, is that the wheel gives silent operation. This is due to a sort of cushion action at the bearing. The conical race 17, being of relatively thin metal, is capable of some flexing movement and as the wheel is subjected to blows in use there is a flexing action in the member 17 which affords this cushion action and results in a silent operation. The bearing may be lubricated by merely dropping oil into the bearing portion, but it may be pointed out that severe tests have been made without lubrication and the findings were that successful operation can be had without lubrication. The wheel may be used elsewhere than for rollers for skates.

I claim:

1. A wheel comprising a cup-shaped metal blank, the flange of which forms the rim of the wheel, said flange tapering in thickness with the greatest thickness near its free edge, a complementary sheet metal blank telescoping within the cup-shaped blank, the outer surface of the rim of the cup-shaped blank lying substantially parallel to the axis, and the inner surface lying at an angle to the axis, said complementary portion having its periphery in engagement with the inclined inner walls of said flange.

2. A wheel comprising a cup-shaped blank, the flange of which forms a wheel rim, the wall of the flange being tapered in thickness with the outer surface substantially parallel to the axis and the inner surface angular as regards the axis whereby the cup-shaped member is of re-entrant form, a complementary cup-shaped blank telescoped within the first mentioned cup-shaped portion and held therein by the inclined inner surface of the flange.

3. A wheel comprising a cup-shaped sheet metal blank having a central aperture, a conical shaped part around the aperture, the flange of the cup forming a wheel rim and the cross-section of the flange tapering in thickness with the greater thickness at its free edge, the outer wall of the rim substantially paralleling the axis and the inner wall inclining toward the axis, a complementary sheet metal blank of cup shape having a central aperture and having a conical shaped part around the aperture, the rim of the complementary blank being telescoped within the rim of the first mentioned blank, and the two blanks being held in assembled relation by the said inclined walls.

4. A wheel comprising a cup-shaped sheet metal blank having a central aperture, a conical shaped part around the aperture, the flange of the cup forming a wheel and the cross-section of the flange tapering in thickness with the greater thickness at its free edge, the outer wall of the rim substantially paralleling the axis and the inner wall inclining toward the axis, a complementary sheet metal blank of cup shape having a central aperture and having a conical shaped part around the aperture, the rim of the complementary blank being telescoped within the rim of the first mentioned blank, and the two blanks being held in assembled relation by the said inclined walls, a hub with a raceway located

in the apertures, the said conical shaped parts being reversely formed to provide a V-shaped raceway, and a series of ball bearings confined in the raceways.

5. A wheel comprising a cup-shaped sheet metal blank having a central aperture, a conical shaped part around the aperture, the flange of the cup forming a wheel rim and the cross-section of the flange tapering in thickness with the greater thickness at its free edge, the outer wall of the rim substantially paralleling the axis and the inner wall inclining toward the axis, a complementary sheet metal blank of cup shape having a central aperture and having a conical shaped part around the aperture, the rim of the complementary blank being telescoped within the rim of the first mentioned blank, and the two blanks being held in assembled relation by the said inclined walls, a hub with a circumferential groove fitting freely within the apertures, the said conical shaped parts being reversely formed to provide a V-shaped raceway, and a series of ball bearings confined between the raceway and the circumferential groove in the hub.
10. 6. A wheel comprising a cup-shaped member with a central aperture, another cup-shaped member telescoped within the first mentioned cup-shaped member and having a central aperture, said members having parts around the apertures of conical shape whereby the parts are separated to form a raceway, a hub freely fitting in the apertures and having a raceway, a series of ball bearings confined between the said raceways, one of the cup-shaped members having 15 radially disposed raised portions forming channels connecting the raceways to the outer portions of the members, and one or more apertures in one of the members near the outer portion thereof.
20. 7. A wheel comprising a cup-shaped member, a complementary cup-shaped member telescoped within the first cup-shaped member with the cup

formations of both members opening in the same direction, the body portions of the cup shaped members being flush against each other, the inner walls of the flange of the first mentioned cup-shaped member inclining toward the axis whereby the first mentioned cup-shaped member is of re-entrant formation and whereby the second mentioned member is held telescoped within the first, both of said members having a central aperture with reversely formed conical parts around their respective apertures, a hub with a circumferential raceway freely fitting within the apertures, said conical parts diverging from each other toward the axis to provide a raceway, and a series of ball bearings confined between the said raceways.

25. 8. A wheel comprising a cup-shaped member, a complementary cup-shaped member telescoped within the first cup-shaped member with the cup formations of both members opening in the same direction, the body portions of the cup shaped members being flush against each other, the inner walls of the flange of the first mentioned cup-shaped member inclining toward the axis whereby the first mentioned cup-shaped member is of re-entrant formation and whereby the second mentioned member is held telescoped within the first, both of said members having a central aperture with reversely formed conical parts around their respective apertures, a hub with a circumferential raceway freely fitting within the apertures, said conical parts diverging from each other toward the axis to provide a raceway, and a series of ball bearings confined between the said raceways, the second mentioned cup-shaped member having a series of radially disposed raised portions simulating spokes forming channels connecting the raceways and the outer portions of the members, one of said members having one or more apertures therein communicating with said passages.

ALFRED T. KVARNSTROM.
